US0D1106946S

(12) **United States Design Patent** (10) Patent No.: **US D1,106,946 S**
(45) Date of Patent: ** Dec. 23, 2025

(54) **CHARGING APPARATUS**

- (71) Applicant: **SHENZHEN SMARTSAFE TECH CO., LTD.**, Guangdong (CN)
- (72) Inventors: **Wei Zhan**, Guangdong (CN); **Shaoli Gu**, Guangdong (CN); **Qingwei Wang**, Guangdong (CN)
- (73) Assignee: **SHENZHEN SMARTSAFE TECH CO., LTD.**, Guangdong (CN)

(**) Term: **15 Years**

(21) Appl. No.: **29/943,938**

(22) Filed: **May 24, 2024**

(57) **CLAIM**

The ornamental design for a charging apparatus as shown and described.

DESCRIPTION

FIG. 1 is a front, left, and bottom side perspective view of a charging apparatus;

FIG. 2 is a rear, right, and top side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included to show features that form no part of the claimed design.

1 Claim, 8 Drawing Sheets
